UNITED STATES PATENT OFFICE.

EDWIN W. WILSON, OF CHICAGO, ILLINOIS.

LAMP.

1,184,400.

Specification of Letters Patent. Patented May 23, 1916.

Application filed October 9, 1913. Serial No. 794,252.

To all whom it may concern:

Be it known that I, EDWIN W. WILSON, a citizen of the United States, residing at Chicago, in the county of Cook and State of Illinois, have invented certain new and useful Improvements in Lamps, of which the following is a full, clear, concise, and exact description, reference being had to the accompanying drawings, forming a part of this specification.

My invention relates to lamps, particularly lamps for automobiles and other vehicles, and its object is to produce a device of this class comprising means whereby the strength of a beam of light emitted from the lamp may be readily varied as desired.

Many cities have of late passed ordinances preventing the use of automobile lamps which throw extremely bright beams of light. Automobilists have, therefore, resorted to a great many makeshifts to comply with these ordinances, as for instance, by clouding the glass in front of an ordinary automobile lamp to prevent light rays passing readily from the lamp.

Such arrangements as the one just mentioned are, of course, subject to the objection that when it is desirable to have the lamps emit beams of light strong enough to illuminate a very dark street or country road, considerable time and exertion is required to clean the glass in the front of the lamps.

Broadly, the device of my invention comprises a casing and a plurality of lighting devices having different lighting properties disposed in the casing and adapted to be brought into operative position one after the other as desired.

The preferred embodiment of my invention comprises a casing and a plurality of lighting units mounted upon a common shaft, each unit comprising a reflector and an electric lamp or other light source, the strength of a beam of light emitted from the lamp at any one time being determined by the reflecting properties of the reflector in operative position at that particular time.

My invention is fully set forth in the following description and is illustrated in the accompanying drawings, in which—

Figure 1 is a longitudinal sectional view of the lamp of my invention; Fig. 2 is a view thereof taken on the line 2—2 of Fig. 1 and looking in the direction of the arrows, and Fig. 3 is an isolated face view of the commutator that controls the circuits for the

several electric lamps forming a part of the device of my invention.

Similar reference numerals refer to similar parts throughout the several views.

As illustrated in the drawings, the lamp of my invention comprises a substantially cylindrical casing 4 provided with a suitable cap or rear end closure 5. A stationary reflector illustrated at 6 is provided with a flange 7 which abuts against the front of the cylindrical casing 4. The glass window 8 is held in position and clamped against the flange 7 of the stationary reflector 6 by means of a collar 9 which encircles the forward end of the cylindrical casing 4 and is provided with an inwardly-extending flange 10 which engages the glass 8.

Secured to the casing 4 by means of screws 11 and disposed on diametrically opposite sides of said casing, are the brackets 12. Suitable uprights 13 carried by an automobile or other vehicle extend through suitable apertures in the brackets 12, the lamp being adjusted in any desired position by means of suitable thumb-screws 14. It is, of course, immaterial how the lamp is mounted or where it is mounted. I have merely described one of many forms of mounting means which may be employed if desired.

Extending transversely of the casing 4 and intersecting the axis thereof is a rotatable shaft 15 which may be journaled in the brackets 12 if desired. At one end the shaft is provided with a suitable handle 16, as shown. Rigidly mounted upon the shaft 15 is a pair of metal disks 17 and 18 which serve to support a plurality of reflectors which will presently be referred to. Suitable spacing bushings 19 may be interposed between the faces of the disks just referred to and the casing 4 if desirable. Soldered or otherwise secured to the metal disks 17 and 18 are the reflectors 19, 20 and 21 which are disposed around the shaft 15 in substantially triangular arrangement. Adjacent reflectors are also soldered or otherwise secured to suitable spacing and securing means illustrated at 22. It should be noted that the reflectors 19, 20 and 21 are of different curvatures, the reflector 19 having very little curvature, the reflector 20 being curved considerably more than the reflector 19, and the reflector 21 being given a conformation very similar to the conformation of the ordinary parabolic reflectors used in automobile lamps of the searchlight type.

Carried by each of the reflectors and formed integrally therewith, if desired, is an electric lamp socket 23. Screwed into each of the sockets 23 is a suitable incandescent lamp 24, the lamp associated with the reflector 19 being frosted as illustrated, if desired.

Carried by the shaft 15 and insulated therefrom, as clearly shown in Fig. 1, are the strips 25, preferably of copper, each one of which is engaged by the insulated terminal of one of the incandescent lamps 24.

Carried by the metal disk 18 is a commutator comprising a disk 26 of insulating material retained in position by a plurality of screws 27. Carried by the disk 26 are three pairs of contact buttons, the buttons 28 being connected by suitable conductors 29 with the copper strips 25 which have electrical engagement with the insulated terminals of the electric lamps 24, and the buttons 30 being electrically connected by conductors 31 or otherwise with the disk 18. As the disk 18 is soldered or otherwise secured to the metallic reflectors it will readily be seen that each one of the buttons 30 is in fact electrically connected with the grounded terminal of one of the electric lamps 24.

Carried by the casing 4 and insulated therefrom are a pair of brushes 32 and 33 which bear against the disk 26 of the commutator and are brought simultaneously into electrical engagement with the contact buttons of each pair as the shaft 15, and consequently the commutator, is rotated. The brushes 32 and 33 are connected with any suitable source of current by means of suitable flexible conductors 34. Whenever the brushes 32 and 33 are brought into engagement with any pair of the buttons 28 and 30 the circuit for the electric lamp whose terminals are connected with said buttons is closed and the electric lamp whose circuit is closed is always the electric lamp located adjacent the stationary reflector 6.

From the above description, it is evident that when the reflector 19 is disposed adjacent the stationary reflector 6 a comparatively weak beam of light will be emitted from the lamp; that a stronger beam will be emitted from the lamp when the reflector 20 is in the position shown in the drawings, and that a very strong beam of light will be emitted from the lamp when the reflector 21 is disposed adjacent the stationary reflector 6.

While I have indicated that the strength of a beam of light emitted from the lamp may be varied by providing reflectors of different curvatures, I may employ electric lamps of different voltages and so secure different degrees of illumination from the several lamps. The embodiment illustrated in the drawings is, however, the preferred one.

Carried by the casing 4 is a spring-pressed plunger 35 which serves to retain the shaft and parts carried thereby at any desired position. The plunger is arranged to coact with suitable notches in the disk 17.

If for any reason it is desirable to place lamps having different colored bulbs in the several lamp sockets, this may, of course, be done without in any way departing from the invention herein disclosed.

While I have illustrated my invention in the particular embodiment herein shown and described, I wish to claim broadly any equivalents thereof which may suggest themselves to those skilled in the art.

What I claim is:

1. A device of the class described, comprising a casing, a plurality of reflectors of different curvatures comprising a unitary structure within the casing, each of said reflectors adapted to be brought into operative position, and a source of light associated with each reflector.

2. A device of the class described comprising a casing, a shaft mounted in the casing, a plurality of reflectors of different curvatures mounted upon said shaft, each of said reflectors adapted to be brought into operative position, and a source of light carried with each reflector.

3. A device of the class described comprising a casing, and a plurality of light reflectors having different light reflecting properties comprising a unitary structure disposed in the casing, each of said reflectors adapted to be brought into operative position.

4. A device of the class described comprising a casing, a shaft mounted in the casing, a plurality of light reflectors of different curvatures mounted on said shaft, said reflectors adapted to be brought into operative position one after the other, an electric lamp associated with each reflector, a commutator mounted on said shaft controlling the circuits for said lamps, and means for rotating said shaft.

5. A lamp comprising a casing, a shaft mounted in the casing, three light reflectors having different light reflecting properties disposed in triangular arrangement upon said shaft, and means for turning said shaft to bring said reflectors into and out of operative position one after the other.

6. A lamp comprising a casing, a shaft mounted in the casing, three light reflectors having different light reflecting properties disposed in triangular arrangement upon said shaft, a detent arranged to retain each of the said reflectors in proper position, and means for turning said shaft to bring said reflectors into and out of operative position one after the other.

7. A lamp comprising a casing, a shaft mounted in the casing, three parabolic re-

reflectors of different curvatures disposed in triangular arrangement upon said shaft, an electric lamp associated with each reflector, and circuit-closing mechanism disposed upon said shaft adapted to close the circuit of each lamp when its associated reflector is brought into operative position.

8. A device of the class described comprising a casing, a shaft mounted in the casing, and a plurality of reflectors of different

curvatures mounted upon said shaft, each of said reflectors adapted to be brought into and out of operative position.

In witness whereof, I hereunto subscribe my name this 6th day of October, A. D. 1913. 15

EDWIN W. WILSON.
